UNITED STATES PATENT OFFICE.

CHARLES MARKHAM CONDER AND GODFREY TWYNAM VIVIAN, OF CAMBORNE,
ENGLAND.

ROLLER-MILL FOR CRUSHING MATERIALS SUCH AS STONE OR ORES.

1,383,529.

Specification of Letters Patent.

Patented July 5, 1921.

Application filed January 26, 1921. Serial No. 440,226.

To all whom it may concern:

Be it known that we, CHARLES MARKHAM CONDER and GODFREY TWYNAM VIVIAN, both subjects of the King of Great Britain, and 5 both residing at Camborne, in the county of Cornwall, England, have invented certain new and useful Improvements in and Relating 10 to Roller-Mills for Crushing Materials Such as Stone or Ores, for which we have filed an application in England, January 24, 1920, of which the following is a specification.

This invention relates to roller mills for crushing materials such as stone or ores 15 wherein a pair of rolls rotated in opposite directions, are pressed toward each other so as to exert a crushing or squeezing pressure on the material fed into the machine. There is a relation between the size of material 20 fed to the machine and the crushed product, which is controlled by the "angle of nip" or the angle at which the rock or the like, is gripped by and drawn down between the rolls. The object of the present invention 25 is to increase this angle, and this is done by mounting the roller shafts in bearings resting on slide blocks at an angle to the horizontal, hereinafter more fully set forth. Certain other improvements are introduced, rendering the machine of simpler 30 construction, and more convenient in use, and will be described hereinafter with reference to the accompanying drawings wherein:

35 Figure 1. shows a side elevation of the machine, partly in section.

Fig. 2. shows an end elevation partly in section.

Fig. 3. shows a plan of the machine and 40 Fig. 4. shows a detail view.

Referring to the drawings, 1 indicates the base or frame of the machine while 2 indicates the wearing plates arranged at an angle to the horizontal, and adapted to support 45 the swivel slide plates 3. The plates 3 are provided with a hole as shown at 30, to enable the roller shaft journals 4 to swivel slightly in the event of a lump of ore or rock forcing one side of the rolls 32 apart more 50 than the other and thus allowing the roller shafts to swivel about their journal centers. By arranging the slide plates 3 supporting the roller journals 31 at an angle as de-

scribed, the rolls and their shafts tend to slide toward one another, so that their 55 weight, which is considerably due to the nature of their work may be utilized and thus save a corresponding amount of the spring or weight pressure which is necessary to obtain the requisite crushing pressure. If during the crushing operation a hard lump of material should come between the rolls, this would tend to force the axes 60 of the rollers farther apart, so that the rollers would be forced up-hill on their slides 65 2. The "angle of nip" or angle at which the rock is gripped, is also increased, as the axes of the rolls are raised thus tending to bring the axes of the rolls and the material, which is being crushed, to a straight line. It is obvious 70 that the nearer a straight line opposite crushing forces are employed to operate alone, the greater the efficiency, and also the resulting pressure. On each side of the journals 31 of the roller shaft 19 there is 75 provided a dust collar 5 for preventing any material from entering the journals. According to the present construction the springs 29 employed act at right angles to the axes of the shafts 19, and by employing 80 them to operate through a toggle device, the number of springs is reduced. Referring to the drawings it will be seen that each roller journal 31 has lugs 34 cast thereon. These lugs 34 support pins 6 which carry 85 short connecting rods 7 hinged at their other ends at 35 to a base plate 8. On the upper side of this plate 8 are mounted compression springs 29 adjusted by a number of tension bolts 9 held at their lower end 33 in the frame 1, while the nuts 11 at their upper 90 end press against the pressure plate 10. By tightening or loosening these nuts 11 the pressure exerted by the springs 29 on the connecting rods 7 thus tending to draw the 95 roller shafts toward one another, may be increased or reduced. In order that the rolls 32 may be adjusted to remain at a minimum distance between their axes, while still allowing them to move apart during 100 working wedge shaped members 12 are placed between the journals 31 and the frame 1. These wedge shaped members which are provided with a recess at 35 to accommodate the lugs 34, pins 6 and arm 7, 105 are adapted to be adjusted by nuts 13 work-

ing on threads on shanks 36, and pressing against lugs 37 cast on frame 1. During working the tendency would be for the wedges 12 to be forced downward so that the threads on their shanks 36 would be stripped or burst. In order to avoid this auxiliary wedges 14 are provided to support the wedges 12 and working at right angles thereto. These wedges 14 have spigots 38 running through holes in the frame 1 and may be adjusted by means of nuts 15 working on threads formed on the spigots 38. Should it be found necessary in operation to increase the minimum distance between the roll axes, the nuts 13 would be tightened, thus raising the wedges 12, then the nuts 15 would be tightened until the auxiliary wedges 14 were tight against the main wedges 12.

20 The rolls 32 are of usual construction and each consists of a roll shell or tire 16 supported by coned shaped hearts or centers 17 engaging in the double coned inner face of the tire 16. The hearts 17 may be forced together by means of bolts 18 thus holding the tire 16 securely to the coned hearts 17, which in turn are mounted on shafts 19 to which they are keyed. To prevent the escape of dust or material, a cover or case is provided 25 in sections 20, 26 of a convenient size, the central section 20 supporting cheek plates 21 which prevent material spilling off the face of the rolls. These cheek plates 21 are held up by means of bolts 22, while the distance between the cheek plates and the rolls 30 may be regulated by threaded distance pins 23 passing through tapped holes in the cover section 20. On the top of the cover 20 is mounted a feed hopper 24.

35 One end of each shaft 19 is extended and driving pulleys 28 mounted thereon, for driving the shafts in opposite directions. If desired the pulleys may be driven at different speeds to obtain a grinding action 40 necessary for certain materials.

45 Having thus described our invention

what we claim as new and desire to secure by Letters Patent is:—

1. A roller crushing mill comprising a frame with vertical and inclined bearing surfaces, journals mounted on said inclined bearing surfaces, shafts mounted in said journals, rolls keyed to said shafts, driving pulleys on said shafts, toggle levers connecting together said journals, spring means acting on said toggle levers and adapted to draw the journals toward one another, and wedge members with means for adjusting same between the journals and the vertical bearing surfaces. 50

15 2. A roller crushing mill comprising a frame with vertical and inclined bearing surfaces thereon, journals mounted on the inclined surfaces, rolls mounted in said journals, base plates between said journals, pivoted links connecting the journals to the base plates, plates adapted to slide between the vertical bearing surfaces, a plurality of springs between the plates and the base plates, bolts secured to the frame and passing through said plates, said bolts being adapted for adjusting the pressure of the springs, and wedges between the vertical bearing surfaces and the journals. 65

20 3. A roller crushing mill comprising a frame with vertical and inclined bearing surfaces, journals mounted on said inclined bearing surfaces, shafts mounted in said journals, rolls keyed to said shafts, dust covers for said journals, said dust covers being mounted on the shaft, driving pulleys on said shafts, toggle levers connecting together said journals, spring means acting on said toggle levers and adapted to draw the journals toward one another, wedge members with means for adjusting same between the journals and the vertical bearing surfaces, and a casing with a hopper for inclosing the rolls. 70

CHARLES MARKHAM CONDER.
GODFREY TWYNAM VIVIAN.
